UNITED STATES PATENT OFFICE.

CHARLES COMSTOCK, OF RACINE, WISCONSIN.

PLATFORM-SPRING CONNECTION.

SPECIFICATION forming part of Letters Patent No. 274,277, dated March 20, 1883.

Application filed August 31, 1882. (No model.)

To all whom it may concern:

Be it known that I, CHARLES COMSTOCK, of Racine, in the county of Racine, and in the State of Wisconsin, have invented certain new and useful Improvements in Spring-Connections for Half-Platform Wagons; and I do hereby declare that the following is a full, clear, and exact description thereof.

My invention relates to what are known as "half-platform spring-wagons," and it consists in a device for connecting the middle bar to the rear side springs, as will be fully described hereinafter.

In the drawings, Figure 1 is a perspective view of the rear gear of a half-platform wagon, and Figs. 2 and 3 are details.

A is the rear axle. B are the rear side springs; C, the rear cross-spring; D, a bolster carried by the rear cross-spring; E, the reach, and F the middle bar. When the body is in place its rear half is supported by the bolster D and middle bar, F.

It has been found, previous to my invention, very difficult to make a proper connection between the front ends of the springs B and the middle bar, F—that is, a connection that would permit the lengthening and shortening of the spring under pressure, and which would avoid that cramping action of the spring which is so liable to produce fracture; and hence my invention consists in suspending a bracket, B', from each end of the middle bar, the middle bar fitting between ears b b, rising from the top of the bracket B', and at their lower points I provide each bracket with a pair of links, a a, which are pivoted thereto by bolts e, and I pivot the upper ends of links a a, by bolts e', to the front ends of the springs B B.

Now, when the body is at rest the springs B will hold the links a a about vertical. A slight load will throw the links into the position shown in dotted lines, Fig. 2, while a heavy load will return the links to a vertical again, the links yielding to give free play to the front ends of the springs B, and therefore no amount of jostling can cause the springs B to cramp or bind. While the ears b b of my bracket project up to clamp the middle bar, its curved depending portion is curved so as to project under the middle bar in position to support its end of the spring directly beneath the middle bar.

What I claim as my invention, and desire to secure by Letters Patent, is—

1. In combination with the rear cross-spring and rear side springs, B B, and middle bar, F, the brackets B', having ears b b rising therefrom to receive the middle bar, and curved depending portion projecting under said middle bar, at right angles thereto, and the pivoted links a, connected by bolts to the front ends of the rear side springs, substantially as set forth.

2. As a new article of manufacture, the spring-bracket B', consisting of flat top with ears b b projecting vertically therefrom, and curved depending portion at right angles to the length of the top, bolt e, links a a, and bolt e', substantially as set forth.

In testimony that I claim the foregoing I have hereunto set my hand, on this 19th day of August, 1882, in the presence of two witnesses.

CHAS. COMSTOCK.
